UNITED STATES PATENT OFFICE.

ANDREW LITTLE, OF NEW YORK, N. Y.

DESIGN FOR PRINTING-TYPE.

Specification forming part of Design No. 7,202, dated February 24, 1874; application filed December 16, 1873.
[Term of Patent 7 years.]

To all whom it may concern:

Be it known that I, ANDREW LITTLE, of the city, county, and State of New York, have originated and produced a new Design for Printing-Type, of which the following is a specification:

The nature of my design for printing-type

is fully shown in the accompanying typographic impression, to which reference is had.

What I claim as new is—

The design for printing-type, as shown.

Witnesses: ANDREW LITTLE.

Wm. HASTINGS,

A. SIDNEY DOANE.
